(57) **CLAIM**

I claim the ornamental design for a lighting fixture, as shown and described.

DESCRIPTION

FIG. 1 is a perspective view of a lighting fixture in accordance with a first embodiment of the present invention;

FIG. 2 is a front view thereof;

FIG. 3 is a left-side view thereof;

FIG. 4 is a right-side view thereof;

FIG. 5 is a rear view thereof;

FIG. 6 is a top view thereof;

FIG. 7 is a bottom view thereof;

FIG. 8 is a perspective view of a lighting fixture in accordance with a second embodiment of the present invention;

FIG. 9 is a front view thereof;

FIG. 10 is a left-side view thereof;

FIG. 11 is a right-side view thereof;

FIG. 12 is a rear view thereof;

FIG. 13 is a top view thereof;

FIG. 14 is a bottom view thereof;

FIG. 15 is a perspective view of a lighting fixture in accordance with a third embodiment of the present invention;

FIG. 16 is a front view thereof;

FIG. 17 is a left-side view thereof;

FIG. 18 is a right-side view thereof;

FIG. 19 is a rear view thereof;

FIG. 20 is a top view thereof;

FIG. 21 is a bottom view thereof;

FIG. 22 is a perspective view of a lighting fixture in accordance with a fourth embodiment of the present invention;

FIG. 23 is a front view thereof;

FIG. 24 is a left-side view thereof;

FIG. 25 is a right-side view thereof;

FIG. 26 is a rear view thereof;

FIG. 27 is a top view thereof; and,

FIG. 28 is a bottom view thereof.

(Continued)

The broken lines in the drawings are provided for environment only and form no part of the claimed design.
